(57) **CLAIM**

The ornamental design for a free standing valet and mirror, as shown and described.

DESCRIPTION

FIG. 1 is a perspective view of the free standing valet and mirror of the present invention;

FIG. 2 is a front elevational view of the invention shown in FIG. 1;

FIG. 3 is a rear elevational view of the invention shown in FIG. 1;

FIG. 4 is a left side elevational view of the invention shown in FIG. 1;

FIG. 5 is a right side elevational view of the invention shown in FIG. 1;

FIG. 6 is a top plan view of the invention shown in FIG. 1; and,

FIG. 7 is a bottom plan view of the invention shown in FIG. 1.

The broken lines in FIG. 1 of the drawing disclosure illustrate environment and form no part of the claimed design.
